ABSTRACT

Apparatus for connecting a sensor used in a contactless ignition system in the distributor of a vehicle including an adaptor plate with breakaway portions for fitting the plate to different types of internal combustion engine distributor housings. The timing sensor is connected to the adaptor plate in a spaced relation to the distributor cam. The adaptor plate in turn is connected to an advance plate within the distributor housing utilizing connecting means originally used to connect the breaker points to the advance plate.

DISTRIBUTOR SENSOR ADAPTOR

BACKGROUND OF THE INVENTION

Electronic ignition systems have been developed and utilized in internal combustion engines. One utilizing a timing sensor in the distributor instead of the traditional breaker points is shown and taught in Hufton, U.S. Pat. No. 3,390,668, assigned to the assignee of this application. Generally, the conversion of a conventional breaker point vehicle ignition system to timing sensor operation has required permanent changes in the distributor including machine work, the dismanteling of the distributor and the substitution of parts. To further add to the complexity of the situation distributors in different vehicles have different configurations, the breaker points are secured in different positions and by different means and the rotors may even rotate in different directions.

SUMMARY OF THE INVENTION

An object of this invention is to provide a simple and economical device for converting a plurality of different internal combustion engine distributors from breaker point operation to timing sensor operation.

A further object of this invention is to provide a method and apparatus for conversion of a motor vehicle distributor from breaker point operation to timing sensor operation without the necessity of undertaking permanent alterations to the distributor.

In one embodiment of the invention the breaker points, condenser and lead wire connected to the breaker points are removed. Two flat head screws are then inserted and secured in designated recessed holes in the adaptor plate depending upon the type of distributor. Next, the adaptor plate is positioned within the distributor housing with the screw heads sandwiched between the adaptor plate and advance plate and secured to the advance plate by the same screws and same tapped holes as were used to secure the breaker points to the

5 with a timing sensor secured thereto in accordance with this invention; and

10 FIG. 4 illustrates a sensor being adjusted with a gapping ring in place between it and the cam.

DETAILED DESCRIPTION

Referring to FIG. 1 the adaptor apparatus is shown installed in the original distributor housing 24. The adaptor plate 10 with the timing sensor 12 and associated securing means 14, 16, 18, 20 is connected to the advance plate 22 within the distributor housing 24.

15 Breakaway tabs 26, 28 and 30 are shown in FIG. 2 as are separation groove 32 between tabs 26 and 28, groove 34 between tab 28 and the main body 31 of the adaptor plate 10 and groove 36 between breakaway tab 30 and the main body 31. Each of the grooves has been channeled into the plate to weaken it without limiting its effectiveness as a mounting plate thereby providing an effective way to remove the tabs as required. The plate is rigid and made of die cast zinc approximately three thirty seconds inch in thickness. It is lightweight, strong, inexpensive and will not easily corrode. It is nonconductive and nonmagnetic.

20 The lettering on the face of the plate (FIG. 3) designates 25 separate holes which are utilized by reference to the following chart when installing the conversion apparatus. The appropriately lettered holes receive the screws for mounting the timing sensor 12. Like parts have been given like numbers in the drawings. The shape of the adaptor plate and holes and indentations around the periphery as shown in FIG. 2 are 30 selected in order to satisfy the requirements for a standard adaptor plate for a plurality of distributors. It was as a result of those same requirements that the breakaway tabs were utilized in the development of the standard plate.

35 The following chart was prepared to indicate how the adaptor plate 10 can be mounted in standard brand vehicles which are indicated therein as Vehicle A, B, C and D. It is not meant to limit the invention in any manner but is shown only as an example of how the adaptor plate has been successfully employed.

Vehicle	Step 1	Step 2	Step 3	Step 4	Step 5	Step 6
Direction of cam rotation	Break off the section of adaptor plate listed below	Attach sensor mounting screws and nuts to the adaptor plate using the two holes and nuts listed below—see Fig. 3	Mount sensor on adaptor plate as in Fig. 1 or turned over as listed below	Install adaptor plate into the distributor using holes listed below—refer to Fig. 3	Adjust gap with gapping ring as illustrated in figure below	Install strain relief grommet as illustrated in figure listed below
Vehicle A: 8-cyl. CCW	30	"Z" holes, thin nuts	Turned over (No. 60 on bottom).	"B" holes	Fig. 4	Fig. 4
Vehicle B: 6-and 8-cyl. CW 6-and 8-cyl. CCW	26 30	"Y" holes, thin nuts "X" holes, thin nuts	Fig. 1 Fig. 1	"C" holes "E" holes	Fig. 4 Fig. 4	Fig. 4 Fig. 4
Vehicle C: 8-cyl. CW 8-cyl. CCW	26 26	"Y" holes, thick nuts "Z" holes, thick nuts	Fig. 1 Turned over (No. 60 on bottom).	"D" holes "D" holes	Fig. 4 Fig. 4	Fig. 4 Fig. 4
Vehicle D: 8-cyl. CW 8-cyl. CCW	26 26	"Y" holes, thick nuts "Z" holes, thick nuts	Fig. 1 Turned over (No. 60 on "D" bottom).	"D" holes	Fig. 4	Fig. 4

advance plate with the distributor in breaker point operation. A designated gapping ring is fitted over the cam to maintain a spaced relation between the distributor cam and sensor which is mounted on the flat head screws and secured by designated nuts. The gapping ring is thereafter removed and finally a strain relief grommet is inserted through the existing lead hole in the distributor housing and secured.

DESCRIPTION OF THE DRAWINGS

FIG. 1 illustrates an exploded view in perspective of the apparatus in accordance with this invention;

FIG. 2 is a bottom plan view of an adaptor plate in accordance with this invention;

FIG. 3 illustrates a top plan view of the adaptor plate of FIG. 75

Referring now to the chart, after the breaker point apparatus has been removed from the distributor the next step is to break away appropriate sections so the plate will fit into the distributor housing. Vehicle C, for example, with a clockwise rotating distributor has been converted as shown in FIG. 1. With two pairs of pliers, one clamped on each side of groove 32, the plate 26, as prescribed by step 1 of the chart, is bent back and forth until it breaks, separating the section 26 from the rest of the plate. The adaptor plate is then the appropriate size for positioning within the distributor housing 24 (FIG. 1).

70 In step 2 the flat head mounting screws 14 and 16 (FIG. 1) are inserted in the recessed holes lettered "Y" in the chart (38 and 40 in FIG. 1) of adaptor plate 10. One of the problems in developing standard apparatus was the axial placement of the timing sensor within the distributor. In the C vehicle the chart

requires the use of "thick" nuts 42 and 44 to secure the mounting screws 14 and 16 to the adaptor plate 10 in comparison to the "thin" nuts used in A vehicles. The thick nuts axially set the sensor 12 relative to the adaptor plate. Whether the "thick" or "thin" nuts are used to secure the mounting screws, the remaining two nuts secure the sensor to the mounting screws. In one instance nuts designated as "thin" nuts are on the order of one-eighth inch and "thick" nuts are on the order of three-sixteenth inch. With the flathead screws secured by nuts 42 and 44 (FIG. 1), the adaptor plate 10 is then positioned within the distributor housing 24 so the screw heads are sandwiched between the advance plate 22 and adaptor plate 10. The adaptor plate 10 is fitted over point nib 48 and secured to the advance plate 22 with screws 50, 51 and 52 inserted through the "D" holes as indicated by step 4, and inserted into tapped holes 54, 55, and 56 in the advance plate. The screws and tapped holes being identical to those originally used in securing the breaker points to the advance plate of the distributor.

In one case for B vehicles, the original breaker point securing means are not used. Instead a longer screw 86 (FIG. 4) is used to secure the adaptor plate in cooperation with a compression ring 88 which fits around point post 90.

The sensor 12 is positioned the same for all B vehicles. However, for A vehicles, and C and D eight cylinder vehicles in counterclockwise operation adapting the distributor requires turning the sensor over so the original top 60 is positioned at the bottom.

In mounting, the sensor (FIG. 1) is fitted over the mounting screws 14 and 16, and secured with nuts 18 and 20 respectively.

For installation, a uniform distance is maintained between the sensor 12 and the cam 58 by a gapping ring such as the ring 70 which is shown in connection with the embodiment illustrated in FIG. 4. The size of the gapping ring is dependent on the relative size of the cam. In the present invention a single gapping ring may be utilized for all the models listed. The gapping ring of spring steel maintains a uniform gap between the cam points 72, 74, 76, 78, 80 and 82 and the sensor 12. Slot 84 as displayed in FIG. 1 permits limited motion of the sensor 12 for adjustment to maintain engagement with the gapping ring.

To complete the conversion of the distributor, a strain relief grommet 92 (FIG. 4) and retaining ring 94 are normally installed to hold the sensor lead 96 in place in the existing lead

hole 100 in the distributor housing (FIG. 4). Enough slack must, however, be allowed in the sensor lead for movement of the advance plate 22. In most automobiles the movement of the advance plate might reach approximately 10° at most.

5 Special note should be made of the absence of damage to the original equipment during conversion. In fact, the reconversion to breaker point operation may still be accomplished. At no time during the conversion is there a need to drill new holes, cut parts to fit, grind, mill or perform any other step of 10 preparing parts other than breaking off appropriate breakaway tabs. Substitution of parts is minimal. The method is straightforward and requires no special skill.

What has been disclosed then is a simple, economical method and apparatus for conversion of any selected one of a 15 plurality of internal combustion engine distributors from breaker point operation to timing sensor operation for a contactless ignition system.

I claim:

1. Adaptor apparatus for converting any selected one of a 20 plurality of different motor vehicle distributors having timing cam means and an advance plate from breaker point operation to timing sensor operation for electronic ignition, said adaptor comprising,

25 an adaptor plate;
a timing sensor;
means for indexing said timing sensor to said adaptor plate;
first connecting means for connecting said sensor to said adaptor plate;
and second connecting means for connecting said adaptor 30 plate to the advance plate thereby positioning said timing sensor in a spaced relation to the timing cam means.

2. The adaptor apparatus according to claim 1 wherein said 35 second connecting means comprises means originally used for connecting the breaker points of said distributor to said advance plate.

3. The adaptor apparatus according to claim 1 wherein said adaptor plate includes breakaway means for adapting said plate to fit a specific distributor housing.

4. The adaptor apparatus according to claim 1 including 40 said adaptor plate having a plurality of indexing means, and further including means for selecting a predetermined indexing means to use for indexing said timing sensor to said adaptor plate.

5. The adaptor apparatus according to claim 4 wherein said 45 predetermined indexing means positions said adaptor plate with respect to the advance plate.
